US0D1003965S

(12) **United States Design Patent** (10) Patent No.: **US D1,003,965 S**
(45) Date of Patent: ** Nov. 7, 2023

(54) **CAMERA**

(71) Applicant: **Microsoft Corporation**, Redmond, WA (US)

(72) Inventors: **Timothy G. Escolin**, Seattle, WA (US); **Jazmine Ama Hoyle**, Seattle, WA (US); **Byungkwan Min**, Kirkland, WA (US); **Ralf Groene**, Kirkland, WA (US); **Panos Costa Panay**, Redmond, WA (US); **Young Soo Kim**, Bellevue, WA (US)

(73) Assignee: **Microsoft Corporation**, Redmond, WA (US)

(**) Term: **15 Years**

(21) Appl. No.: **29/808,701**

(22) Filed: **Sep. 22, 2021**

(51) LOC (14) Cl. **16-05**

(52) U.S. Cl.

USPC **D16/219**

(57)

CLAIM

The ornamental design for a camera, as shown and described.

DESCRIPTION

FIG. 1 is a front perspective view of a camera showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The even-length broken lines in the drawings illustrate portions of the camera that form no part of the claimed design.

1 Claim, 5 Drawing Sheets
